CLAIM

We claim the ornamental design for a portable computer with barcode reader, as shown and described.

DESCRIPTION

FIG. 1 is a perspective front view of a portable computer with barcode reader according to the present invention.

FIG. 2 is a perspective rear view of a portable computer with barcode reader of FIG. 1.

FIG. 3 is a front elevation view of the portable computer with barcode reader of FIG. 1.

FIG. 4 is a rear elevation view of the portable computer with barcode reader of FIG. 1.

FIG. 5 is a left side elevation view of the portable computer with barcode reader of FIG. 1.

FIG. 6 is a right side elevation view of the portable computer with barcode reader of FIG. 1.

FIG. 7 is a bottom view of the portable computer with barcode reader of FIG. 1.

FIG. 8 is a top view of the portable computer with barcode reader of FIG. 1.

(Continued)

FIG. 9 is a perspective front view of a second embodiment of a portable computer with barcode reader according to the present invention.

FIG. 10 is a perspective rear view of a portable computer with barcode reader of FIG. 9.

FIG. 11 is a front elevation view of the portable computer with barcode reader of FIG. 9.

FIG. 12 is a rear elevation view of the portable computer with barcode reader of FIG. 9.

FIG. 13 is a left side elevation view of the portable computer with barcode reader of FIG. 9.

FIG. 14 is a right side elevation view of the portable computer with barcode reader of FIG. 9.

FIG. 15 is a bottom view of the portable computer with barcode reader of FIG. 9; and,

FIG. 16 is a top view of the portable computer with barcode reader of FIG. 9.

The broken lines shown are included for the purpose of illustrating portions of the portable computer with barcode reader that form no part of the claimed design.
